UNITED STATES PATENT OFFICE.

JOHN MAGEE, OF BROOKLYN, NEW YORK, ASSIGNOR TO THE BIGELOW CARPET COMPANY, OF CLINTON, MASSACHUSETTS.

DESIGN FOR CARPET.

Specification forming part of Design No. 10,874, dated October 22, 1878; application filed October 1, 1878.
[Term of patent 3½ years.]

To all whom it may concern:

Be it known that I, JOHN MAGEE, of Brooklyn, Kings county, New York, have invented a new and original Design for a Carpet, of which the following is a specification:

This invention relates to a new design for a carpet, oil-cloth, or similar fabric.

The accompanying photograph illustrates my newly-designed carpet, and conveys to any one skilled in the art a full description of my invention, enabling him to use the same.

The design may be applied in suitable colors.

I claim—

The design for a carpet, substantially as shown.

JOHN MAGEE.
